UNITED STATES PATENT OFFICE.

JOHN W. FREY, OF WEBB CITY, MISSOURI.

GAME APPARATUS.

SPECIFICATION forming part of Letters Patent No. 498,781, dated June 6, 1893.

Application filed February 1, 1893. Serial No. 460,542. (No model.)

To all whom it may concern:

Be it known that I, JOHN W. FREY, a citizen of the United States, residing at Webb City, in the county of Jasper and State of Missouri, have invented certain new and useful Improvements in Game Apparatus; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention has for its object to provide a new and useful construction in game apparatus, and it consists of a suitable labyrinth which is covered over, the cover having impressed thereon a diagram of the labyrinth and a suitable spherical body being contained in the labyrinth, which may by the various inclinations given to the apparatus be caused to traverse the labyrinth, and my invention also consists in the construction, arrangement and combination of the several parts of which it is composed, as will be hereinafter more fully described and claimed.

Referring to the accompanying drawings in which corresponding parts are designated by similar marks of reference, Figure 1 is a plan view of a game apparatus constructed according to this invention. Fig. 2 is a plan view with the cover removed. Fig. 3 is a vertical section on lines $\alpha\alpha$ of Fig. 2.

As shown in the accompanying drawings the device consists of an imperforated bottom 1, and a perforated top 2, between which is contained the body or block 3, although it is obvious that the bottom and block may be formed of a single piece of material, the said block having formed therein depressions which constitute the hereinafter described labyrinth, and that the block may be formed of any desired material, and have the top secured thereto in any desired manner. As shown in the annexed drawings, the block is rectangular in shape and has projecting from opposite sides thereof, toward its center, which is cut out, a series of tongues or fingers 4, the said tongues or fingers, by preference, projecting from alternate points on the opposite side of the block, thus forming a series of pockets 5, and as the tongues or fin-

gers are of unequal length, a serpentine connecting passage 6 between the several pockets, constituting a labyrinth, although I do not confine myself to the hereinbefore form thereof, as any desired shape of fingers or partitions separating the several pockets may be used. If preferred, any or all of the said fingers may have their ends curved or bent, as is shown at 7, Fig. 2. The cover 2, which as before stated fits over the block has printed, engraved or otherwise impressed thereon an accurate diagram of the labyrinth hidden thereby, and has a series of apertures 8 therein over the several pockets 5, formed by the fingers 4, the said apertures having impressed on the top near them a series of continuously-designating marks, although it is obvious that if preferred, the said apertures may be only placed over some of the pockets, instead of all, as hereinbefore described. A suitable spherical body or ball 9 is also provided of such a size as will permit its passage through any or all of the said apertures, and will permit its ready movement within the labyrinth.

Such being the construction of my device, the method of its use is as follows: The player inserts the spherical body through the aperture, having the first in order of the designating marks near it, and endeavors by various inclinations of the apparatus to cause the spherical body to appear below the aperture which has the succeeding number near it. He then endeavors in a similar manner to cause it to appear below the aperture next in order, until he has succeeded, by successive inclinations of the apparatus in causing the body to appear beneath the last of the said apertures, he having then solved the puzzle. If at any time the spherical body appears beneath the wrong aperture, he has made a miss, and must remove the spherical body and start again from the first aperture. When several are playing, the method of using the apparatus may be varied, and any player making a miss must pass the apparatus to the player next in order, and must start when the apparatus has again come round to him, either at the first aperture, or the aperture below which the spherical body was situated prior to his miss in the previous play, as may be decided. The player first making the last aperture is the winner.

It will be noted that the spherical body is except when under the aperture, hidden from sight, as is also the labyrinth in which it is contained, the diagram of the latter upon the top, being the only guide the player has to determine in what manner to incline the apparatus.

Having thus described my invention, what I claim is—

- 10 1. In a game apparatus, the combination with a suitable body having a labyrinth formed therein, and having an apertured top with a diagram of the said labyrinth impressed thereon, of a spherical body adapted to be moved through the said labyrinth, substantially as described.
- 15 2. In a game apparatus, the combination with a suitable body having a labyrinth therein, of a cover therefor, having a series 20 of apertures therein, the said cover having impressed thereon a diagram of the said labyrinth, and a series of marks designating the order of the said apertures, and a spherical body adapted to be moved through the said labyrinth, substantially as described.
- 25 3. In a game apparatus, the combination with a suitable body, having a labyrinth therein, and provided with a series of pockets forming a part of said labyrinth, of a cover 30 for the said body, having a series of apertures therein, located over the several pockets, the said cover having impressed thereon a diagram of the said labyrinth, and a series of marks designating the order of the said apertures, and a spherical body adapted to be moved through the said labyrinth, substantially as described.
- 35 4. In a game apparatus, the combination with a suitable body, or block, having its inferior cut out, and having a series of fingers 40 projecting from its opposite sides, forming pockets and a labyrinth, of which the said pockets are a part, an imperforated bottom

for the said block, and a cover therefor, having a series of apertures therein located over the 45 several pockets, the said cover having impressed thereon, a diagram of the said labyrinth, and a series of marks designating the order of the said apertures, and a spherical body adapted to be moved through the said 50 labyrinth, substantially as described.

5. In a game apparatus, the combination with a suitable block, and having a series of fingers of unequal length projecting from alternate points of its opposite sides, forming 55 60 pockets and a serpentine passage connecting them, which said pockets and passage constitute a labyrinth, a bottom and a top for the said block, the said cover having a series of apertures therein, located over the said pockets, and having impressed thereon a diagram of the said labyrinth, and a series of marks designating the order of the said apertures, and a spherical body adapted to be moved through the said labyrinth, substantially as 65 described.

6. In a game apparatus, the combination with a suitable block, having a series of fingers of unequal length projecting from its opposite sides, forming pockets and a serpentine passage connecting them, which said pockets and passage constitute a labyrinth, a bottom and top for the said block, the said cover having a series of apertures therein, located over the said pockets, and having impressed thereon a diagram of the said labyrinth, and a series of marks designating the order of the said apertures, and a spherical body adapted to be moved through the said labyrinth, substantially as described. 70 75 80

In testimony whereof I affix my signature in presence of two witnesses.

JOHN W. FREY.
